(57) **CLAIM**

The ornamental design for a nail clipper, as shown and described.

DESCRIPTION

FIG. 1 is a right side elevation view of the nail clipper;

FIG. 2 is a left side elevation view of the nail clipper;

FIG. 3 is a front elevation view of the nail clipper;

FIG. 4 is a rear elevation view of the nail clipper;

FIG. 5 is a top plan view of the nail clipper;

FIG. 6 is a bottom plan view of the nail clipper; and,

FIG. 7 is a perspective view of the nail clipper.

In the drawings, the broken lines illustrate portions of the article which form no part of the claimed design.
